PIPE OR TUBE MILL

Louis W. Long, Lorain, Ohio, assignor to National Tube Company, a corporation of New Jersey

Application February 4, 1938, Serial No. 188,743

2 Claims. (Cl. 80—13)

This invention relates to pipe or tube mills and, more particularly, to the handling of the mandrel employed therein. Pipe or tube mills of the type to which applicant's invention appertains are composed of two or more power-actuated metal-working rolls in combination with an intermediately disposed mandrel carried by an elongated bar which is secured to a remotely disposed reciprocatory carriage. As the work-piece is gripped by the power-actuated metal-working rolls and moved over the intermediately disposed mandrel it telescopes over this elongated bar. After the trailing end of the work-piece has moved through the power-actuated metal-working rolls and onto the elongated bar, the latter is withdrawn from the interior of the work-piece and kick-up arms actuated to translate it from the mill onto a suitably disposed skidway or other conveying device.

On very large mills, for instance those which produce work-pieces of 20 inches in diameter, the elongated bar, or so-called mandrel-bar, and its carriage weigh over 16,000 pounds and are moved into position at a rate of approximately 500 feet per minute. In producing thin-walled work-pieces, the mandrel on the end of the mandrel-bar must be positioned very close to the power-actuated working-rolls of the mill, and if permitted to over-run its true working position, will occasion considerable damage to the rolls and numerous other parts of the mill.

The work-piece must be completely rolled in a minimum of time if a substantial commercial yield from the mill is to be maintained. This, of course, requires the rapid withdrawing and repositioning of the mandrel-bar.

It is among the objects of the present invention to provide an efficient and inexpensive apparatus for manipulating the mandrel-bar of a pipe or tube mill in a manner which is not only rapid but one which also eliminates damage to the component elements of the latter.

The foregoing and other objects will be apparent after referring to the drawings in which:

Figure 1 is a fragmentary plan of a pair of cone-shaped power-actuated metal-working rolls together with an intermediately disposed mandrel which is supported by a mandrel-bar, all in accordance with conventional practice;

Figure 2 is a plan of the mill of Figure 1 on a smaller scale and disclosing fragmentarily the outlet bed thereof;

Figure 3 is a view similar to that of Figure 2 but disclosing some of the elements of the mill in a different position;

Figure 4 is a view similar to Figure 1 but disclosing a mandrel-bar and the mandrel carried thereby in the usual overrun position which occasions the injurious results which the invention seeks to eliminate;

Figure 5 is an enlarged fragmentary side elevation of the remote end of the outlet bed of Figures 2 and 3;

Figure 6 is a sectional elevation on line VI—VI of Figure 5;

Figure 7 is a plan of the apparatus of the invention;

Figures 8 and 9 are wiring diagrams; and,

Figures 10 through 15 are details of the diagram of Figures 8 and 9, being individual switches employed therein.

Referring more particularly to the drawings, the numerals 2 and 3 designate a pair of cone-shaped power-actuated metal-working rolls toward which there is extended a compression mandrel-bar 4 carrying a mandrel-plug 5 which is disposed intermediate the rolls. After a pipe or tube has been completely rolled between the metal-working rolls 2 and 3 and the intermediately disposed mandrel-plug 5, and has moved onto the mandrel-bar 4, it is removed from the mill by withdrawing the mandrel-bar and mandrel-plug and translating the pipe or tube by the usual kick-off arms (not shown), whereupon it is permitted to roll by gravity over a conveniently disposed skidway 6. According to conventional practice, the mandrel-bar 4 is suitably attached to a mandrel-bar carriage 8 which rides on an elongated frame 9 forming part of the outlet bed of the mill.

Referring to Figure 5 of the drawings, a vertical frame 10 is disposed adjacent the elongated frame 9 forming part of the outlet bed of the mill at a position adjacent the position of the mandrel-bar carriage 8 when the latter is in its forward or true working position. A shaft 12 is horizontally supported by the vertical frame 10 immediately above the elongated frame 9. This shaft 12 carries a rotatable latch 13 having a flattened portion 14 on its extended end. The upper surface of the mandrel-bar carriage 8 is provided with an abutment plate 15 having a flattened face 16. At one side of the upper end of the vertical frame 10, there is disposed a fluid-actuated cylinder 17, the piston of which is pivotally connected as at 18 to a crank 19 which is connected to the latch 13.

According to the foregoing construction and arrangement of elements, it will be seen that the deenergization of the fluid-actuated cylinder 17

will permit the lowering by gravity of the latch 13 in such manner as to present its flattened surface 14 for contact with the flattened surface 16 of the abutment plate 15 on the mandrel-bar carriage 8. While in its lowered position, the latch 13 will prevent the displacement of the mandrel-bar carriage 8 by the thrust of the work-piece as it passes over the mandrel-plug 5. The energization of the fluid-actuated cylinder 17, after the telescoping of the work-piece onto the mandrel-bar 4, will raise the latch 13 and permit the rearward movement of the mandrel-bar carriage 8 in a manner to be later described.

15 Referring to Figures 6 and 7, the outlet bed of the mill, which comprises the elongated frame 9, is provided with a pair of substantially spaced grooved pulleys 22 and 23. A cable 24 is strung between the pulleys 22 and 23 and connected 20 at its ends to the mandrel-bar carriage 8. Thus, the driving of either of the pulleys 22 or 23 will move the mandrel-bar carriage 8, the mandrel-bar 4 and the mandrel-plug 5 toward and away 25 from the metal-working rolls 2 and 3 of the mill, for the purposes previously mentioned.

According to the teachings of the present invention, and referring more particularly to Figures 6 and 7 of the drawings, an electric motor 26 is disposed adjacent the elongated frame 9 30 of the outlet bed of the mill with its shaft 27 parallel with but spaced from a shaft 28 to which the pulley 23 is suitably secured. The shaft 27 of the motor 26 is connected to the driving shaft 29 of a speed reducer 30 by means 35 of a suitable coupling 31. The driven shaft 32 of the speed reducer 30 extends at right angles to the driving shaft 29 thereof and carries a spider 33 which is connected thereto through a magnetic clutch generally designated at 34.

40 The spider 33 carries a brake wheel 36 forming part of a magnetic brake generally indicated at 37, and is connected to the shaft 38 of an aligned electric motor 39. The magnetic brake 37 is, in all respects, conventional, being actuated for application by a spring and released 45 against the resistance of the spring by a magnet. It will be noted that the electric motor 39 is considerably larger than the electric motor 26 and is intended to produce considerably more power. The other end of the shaft 38 of the electric motor 39 is connected to the driving shaft 40 of a speed reducer 41 by means of a suitable coupling 42. The driven shaft 43 of the speed reducer 41 extends at right angles 50 with respect to the driving shaft 40 thereof and is connected to the shaft 28 carrying the pulley 23 by means of a suitable coupling 45.

It will be noted that the actuation of either 55 the electric motor 26 or the electric motor 39 will result in the rotation of the shaft 28 carrying the pulley 23 to accordingly move the mandrel-bar carriage 8, providing, of course, the latch 13 is not in a position to lock the mandrel-bar carriage against movement away from the mill.

60 Any suitable and conventional electric wiring circuits, including control devices, may be provided for the various electrically operated instrumentalities.

In operation, a tube A, which is shown as having 65 previously been pierced, is introduced between the metal-working rolls 2 and 3 for movement over the mandrel-plug 5 on the forward end of the mandrel-bar 4. The tube A is moved over the mandrel-plug 5 and mandrel-bar 4 by the helical advancing action of the metal-work-

ing rolls 2 and 3. As soon as the trailing end of the tube A has moved over the mandrel-plug 5 and over the mandrel-bar 4 the fluid-actuated cylinder 17 is energized to raise the latch 13, and the motor 39 is suitably actuated (automatically or otherwise) to rotate the pulley 23 in such manner as to withdraw the mandrel-bar carriage 8 along the elongated frame 9 sufficiently to remove the mandrel-bar 4 from the interior of the tube A and permit the mandrel-plug 5 to drop. The usual kick-off devices (not shown) are then actuated to translate the tube A from the outlet bed of the mill and permit it to roll down the skidway 6.

15 After the energization of the fluid-actuated cylinder 17 to raise the latch 13, the motor 39 is energized in a direction which is reverse to that previously described to return the mandrel-bar carriage 8 to a position which is proximate but short of its initial position. At this time 20 the motor 39 is deenergized, together with the magnetic brake 37 which applies the latter to the brake wheel 36, thereby stopping the motor. The magnetic brake 37 is then energized, together with the smaller electric motor 26 and 25 the magnetic clutch generally designated at 34. This permits the electric motor 26 to operate through the speed reducer 30 to rotate the pulley 23, and accordingly move the cable 24, at a slow speed, a distance which is sufficient to restore 30 the mandrel-bar carriage 8, mandrel-bar 4, and mandrel-plug 5 to their initial working positions. The electric motor 26, magnetic clutch 34 and magnetic brake 37 are then deenergized. The fluid-actuated cylinder 17 is then deenergized 35 to lower the latch 13 into contact with the flattened surface 16 on the abutment plate 15 on the mandrel-bar carriage 8.

The metal-working rolls 2 and 3 are, at this stage of the operation, ready to receive the pipe 40 or tube A and advance the same helically over the mandrel-bar 4 and mandrel-plug 5 which are now returned to their initial metal-working positions in the manner previously described.

Referring to Figures 8 and 9 of the drawings, 45 I have illustrated one form of electric circuit which may be utilized to operate the devices of the invention in the manner previously described. In this diagram, the numerals 100 and 101 designate a pair of suitable main power lines carrying mill voltage, such as 230 volts D. C., and normal voltage is applied to the shunt field 105 of the motor 26. The numerals 106 and 107 designate a pair of control electric lines which carry voltage suitable to operate the control devices 50 hereinafter referred to.

The mandrel-bar carriage 8 operates a reverse limit switch 108, a reverse slow down limit switch 109 which reduces its rearward speed when in its proximate rearward position, a forward limit switch 110, and a forward slow down limit switch 111 which reduces its forward speed when in its proximate forward position.

The latch 13 operates two limit switches, as shown at 112 and 114.

65 The operator's pulpit is provided with a master controller 117, a foot-operated switch 197 and the usual control (not shown) for the fluid-actuated cylinder 17 for the latch 13 which holds the mandrel-bar carriage 8 in its forward position.

70 With the mandrel-bar carriage 8 in its extreme rearward position (that is, with the mandrel-bar 4 and mandrel-plug 5 fully withdrawn from the metal-working rolls 2 and 3), the contacts 108* 75

and 108^b of the reverse limit switch 108 are open; the contacts 109^a and 109^b of the reverse slow down limit switch 109 are open; the contacts 110^a and 110^b of the forward limit switch 110 are closed; and the contacts 111^a and 111^b of the forward slow down limit switch 111 are closed.

The latch 13 is now in the down position, thus the contacts 112^a and 112^b of the latch limit switch 112 and the contacts 114^a and 114^b of the latch limit switch 114 are open.

To move the mandrel-bar carriage 8 forwardly toward the metal-working rolls 2 and 3, the sequence of operation is as follows:

The operator of the mill moves the master controller 111 to the "forward" position, thereby establishing the following circuits:

From the line 107 through the master controller contacts 119 and 121, the contacts 123 and the main line contactor coil 125 to the line 106. This closes the main line contactor 125^a energizing the shunt field 127 from the line 101 to the line 100; from the line 107 through the master controller contacts 119 and 129 through the closed contacts 110^a and 110^b of the forward limit switch 110, the closed reverse interlock contacts 131, and the parallel connected forward contactor coils 133 and 135 to the line 106. This closes the forward contactors 133^a and 135^a. With the forward contactors 133^a, 135^a and main line contactor 125^a closed, a circuit is established from the line 101 through the starting resistance 137 for the large motor 39, the large motor series field 139, the armature 141 of the large motor 39, and the series coil 143 of the magnetic brake 37 to the line 100. This releases the magnetic brake 37, and the large motor 39 starts to drive the pulley 23 to thereby move the mandrel-bar carriage 8 forwardly toward the metal-working rolls 2 and 3.

When the forward contactors 133^a and 135^a are closed, their interlock contacts 133^b and 135^b open, and the interlock contacts 135^c close. With the closing of the interlock contacts 135^c a circuit is established from the line 107 through the armature shunt contactor coil 145, the closed contacts 111^a and 111^b of the forward slow down limit switch 111, to the line 106. This energizes the armature shunt contactor coil 145 which opens a pair of spring-closed contacts 145^a and removes the armature shunt resistance 147. With the interlock contacts 135^c closed, a circuit is also established from the line 107 through the master controller contacts 119 and 149, a dash-pot accelerating relay coil 151 to the line 106. This energizes the dash-pot accelerating relay coil 151 and its contacts 152, 153, 154 and 155 to slowly start to close. As the dash-pot accelerating relay contacts 152, 153, 154 and 155 slowly close they successively establish circuits from the line 107 through the dash-pot accelerating relay contactor coils 152^a, 153^a, 154^a and 155^a to the line 106. This successively closes the contacts 152^b, 153^b, 154^b and 155^b, shorting-out in steps all of the starting resistance 137. The large motor 39 now has full line voltage applied to it and drives the mandrel-bar carriage 8 forwardly toward the metal-working rolls 2 and 3 at maximum speed.

As the mandrel-bar carriage 8 moves forwardly, a projection 159 carried thereby strikes the operating levers of the reverse limit switch 108 and the reverse slow down limit switch 109, thus closing the contacts 108^a and 108^b, and 109^a and 109^b, respectively.

The large motor 39 continues to drive the mandrel-bar carriage 8 forwardly at maximum speed until the projection 159 strikes the operating le-

ver of the forward slow down limit switch 111, thus opening the contacts 111^a and 111^b. This breaks the circuit to the dash-pot accelerating relay coil 151 and the armature shunt contactor coil 145. The dash-pot accelerating relay coil 151 being deenergized opens its contacts 152, 153, 154 and 155, thus opening the circuits to the dash-pot accelerating contactor coils 152^a, 153^a, 154^a and 155^a. These coils, being deenergized, open the contacts 152^b, 153^b, 154^b and 155^b, thus inserting the starting resistance 137 in series with the large motor 39. The armature shunt contactor coil 145 being deenergized, its spring closed contacts 145^a close, thereby applying the armature shunt resistance 147 to the armature 141 of the large motor 39. The combined effect of inserting the starting resistance 137 in series with the large motor 39 and the armature shunt resistance 147 across the armature 141 slows down the motor 39 and yet gives it sufficient torque to continue to slowly drive the mandrel-bar carriage 8 forwardly.

The large motor 39 continues to slowly drive the mandrel-bar carriage 8 forwardly until the projection 159 strikes the operating lever of the forward limit switch 110 and opens the contacts 110^a and 110^b. At the same time the mandrel-bar carriage 8 strikes the latch 13, lifting it, and closing the contacts 112^a and 112^b of the latch limit switch 112. The forward limit switch 110, being open, breaks the circuit to the forward contactor coils 133 and 135, which opens their contacts 133^a and 135^a, thus opening the circuit to the large motor 39 and the magnetic brake 37. The magnetic brake 37 closes, thereby stopping the large motor. Also operated by the forward contactor coils 133 and 135 are the interlock contacts 133^b and 135^b which close, and interlock contacts 135^c which opens.

The latch limit switch 114, now being closed, establishes a circuit from the line 107 through the master controller contacts 119 and 121, the forward interlock 133^b, the reverse interlock 171, a timing relay coil 173, and the contacts 114^a and 114^b of the latch limit switch 114 to the line 106, thus energizing the timing relay coil 173. After about one second the timing relay coil 173 closes the contacts 173^a and the contacts 173^b. The contacts 173^b establish a circuit from the line 101 through the resistance 175 of the magnetic brake 37 to the line 100, thus energizing and releasing the brake. The contacts 173^b also establish a circuit from the line 101 through the coil of the magnetic clutch 34 to the line 100, energizing and engaging the clutch, thereby mechanically connecting the small motor 26 to the shaft 38 of the large motor 39 through the clutch 34 and the gear reduction 30.

The contacts 173^a of the timing relay coil 173 establish a circuit from the line 107 through the master controller contacts 119 and 121, the forward and reverse interlock contacts 133^b and 171, respectively, a contactor coil 179, and the timing relay contacts 173^a to the line 106, thus energizing the contactor coil 179 which closes the contacts 179^a and opens the contacts 123. The contacts 123 open and break the circuit to the main line contactor coil 125, thereby deenergizing the shunt field 127. The contacts 173^a also establish a circuit from the line 107 through the master controller contacts 119 and 129, interlock contacts 181, and the parallel connected forward contactor coils 183 and 185 to the line 106, thus energizing the forward contactor coils 183 and 185 which closes the contacts 183^a and 185^a and 75

- opens the interlock contacts 183^b. Thus a circuit is established from the line 101 through the contacts 179^a, the starting resistance 187 of the small motor 26, the contacts 185^a, the armature 5 189 of the small motor 26 and the contacts 183^a to the line 100. The small motor 26 starts to drive the mandrel-bar carriage 8 slowly forward through the gear reduction 30, and the magnetic clutch 34.
- 10 The contacts 173^a also establish a circuit from the line 107 through the master controller contacts 119 and 149, and a time delay accelerating contactor coil 191 to the line 106, thus energizing the time relay accelerating contactor coil 191 15 which in about 1/2 second closes contacts 191^a and interlock contacts 191^b. The interlock contacts 191^b parallels an accelerating contactor coil 193 with the time delay accelerating contactor coil 191, thus energizing the accelerating contactor coil 193, which, in about 1/2 second, closes the contacts 193^a. The starting resistance 187 of the small motor 26 is thus shorted-out in two steps, and the armature 189 of the small motor 26 is now across the line.
- 20 The small motor 26 continues to drive the mandrel-bar carriage 8 forwardly until the operating position is reached, at which point the latch 13 drops into position. This opens the contacts 112^a and 112^b and 114^a and 114^b of the latch 25 limit switches 112 and 114, respectively. When the contacts 114^a and 114^b of the limit switch 114 open they break the circuit to the timing relay coil 173 which immediately opens its contacts 173^a and 173^b. The contacts 173^a, being open, break 30 the feed to the contactor coils 179, 183, 185, 191 and 193 which, in turn, opens contacts 179^a, 183^a, 185^a, 191^a, 191^b and 193^a, and closes the contacts 123 and 183^b. These contacts open the circuit to the small motor 26. The contact 173^b, being 35 open, breaks the circuit to the magnetic clutch 34 and the magnetic brake 37, thereby disengaging the clutch and applying the brake to stop the mandrel-bar carriage 8.
- 40 Should the operator desire to advance the mandrel-plug 5 beyond this point for measurement purposes, he may do so by pressing a foot switch 197. This establishes a circuit around the latch limit switch 114 and starts the small motor 26, as previously described. It continues in the forward direction as long as the foot switch 197 is closed and the master controller 117 is in the forward 45 position.
- 45 In order to move the mandrel-plug 5 back from this position to the operating position (that is, with the mandrel-bar carriage 8 against the latch 13), the operator throws the master controller 117 to the reverse position and closes the foot switch 197. This starts the small motor 26 in the reverse direction, as described, except that 50 reverse contactor coils 199 and 201 and contacts 199^a, 181 and 201^a are used in place of the forward contactor coils 183 and 185, and contacts 183^a, 183^b and 185^a, respectively. The mandrel-bar carriage 8 continues to be driven backwardly by the small motor 26 as long as the foot switch 197 is closed and the master controller is in the reverse position.
- 55 After the work-piece is rolled, the operator energizes the fluid-actuated cylinder 17 to lift the latch 13, thereby closing the contacts 112^a and 112^b, and 114^a and 114^b of the latch limit switches 112 and 114, respectively. At the same time the operator throws the master controller 117 to the reverse position, thereby establishing the following 60 circuits:

From the line 107 through the master controller contacts 119 and 121, contact 123 and contactor coil 125 to the line 106, thus closing the contacts 125^a, and energizing the shunt field 127 from the line 101 to the line 100.

From the line 107 through the master controller contacts 119 and 203, the closed contacts 108^a and 108^b of the reverse limit switch 108, contacts 135^a, the parallel connected coils 205 and 207, and the closed contacts 112^a and 112^b of the latch limit switch 112 to the line 106, thus closing the contacts 205^a, 207^a, 205^b and opening the interlock contacts 131 and 171. With the contacts 125^a, 207^a and 205^a closed, a circuit is established from the line 101 through the starting resistance 137, 15 series field 139 of the large motor 39, reverse contactor 207^a, the armature 141 of the large motor 39, reverse contactor 205^a and magnetic brake 37 to the line 100. This releases the magnetic brake 37, and the large motor 39 starts to drive the 20 mandrel-bar carriage 8 away from the metal-working rolls 2 and 3.

At the time the reverse contactors 205^a and 207^a closed, their interlock contacts 131 and 171 opened and 205^b closed. With the contacts 205^b closed, a circuit is established from the line 107 through the armature shunt contactor coil 145, and the reverse slow down limit switch 109 to the line 106, thus energizing the armature shunt contactor coil 145 which opens the spring-closed 30 contacts 145^a. This removes the armature shunt resistance 147. With the contacts 205^b closed, a circuit is also established from the line 107 through the master controller contacts 119 and 149, dash-pot accelerating relay coil 151, and the 35 contacts 109^a and 109^b of the reverse slow down limit switch 109 to the line 106, thus energizing the dash-pot accelerating relay coil 151 whereby its contacts 152, 153, 154 and 155 slowly start to close.

As the dash-pot accelerating relay contacts 152, 153, 154 and 155 slowly close, they successively establish circuits from the line 107 through the dash-pot accelerating contactor coils 152^a, 153^a, 154^a and 155^a to the line 106. This successively energizes the dash-pot accelerating contactor coils 152^a, 153^a, 154^a and 155^a which close the contacts 152^b, 153^b, 154^b and 155^b; thus shorting-out in steps all of the starting resistance 137. The large motor 39 now has line voltage applied to it and drives the mandrel-bar carriage 8 back from the metal-working rolls 2 and 3 at maximum speed.

As the mandrel-bar carriage 8 moves backwardly, the projection 159 again strikes the operating levers of the forward limit switch 110 and the forward slow down limit switch 111, thus reclosing the contacts 110^a and 110^b and 111^a and 111^b.

The large motor 39 continues to drive the 60 mandrel-bar carriage 8 backwardly until the projection 159 strikes the operating lever of the reverse slow down limit switch 109, thus reopening the contacts 109^a and 109^b. This breaks the circuit to the dash-pot accelerating relay coil 65 151 and the armature shunt contactor coil 145. The dash-pot accelerating relay coil 151, being deenergized, opens its contacts 152, 153, 154 and 155, thus opening the circuits to the dash-pot accelerating contactor coils 152^a, 153^a, 154^a and 155^a. These coils being deenergized open the contacts 152^b, 153^b, 154^b and 155^b, thus inserting the starting resistance 137 in series with the large motor 39. The armature shunt contactor coil 145, being deenergized, permits its spring-closed 75

5 contacts 145^a to close, applying the armature shunt resistance 147 to the armature 141 of the large motor 39. The combined effect of inserting the starting resistance 137 in series with the armature 141 of the large motor 39 and the armature shunt resistance 147 across the armature slows down the large motor 39 and yet gives it sufficient torque to slowly drive the mandrel-bar carriage 8 backwardly.

10 The large motor 39 continues to drive the mandrel-bar carriage 8 slowly backward until the projection 159 strikes the operating lever of the reverse limit switch 108, thus reopening the contacts 108^a and 108^b. The reverse limit switch 15 108 being open breaks the circuit to the reverse contactor coils 205 and 207 which open the contacts 205^a, 207^a and 205^b and close the interlock contacts 131 and 171. The contacts 205^a and 207^a being open break the circuit to the large 20 motor 39 and the magnetic brake 37. The magnetic brake 37 closes and stops the large motor 39. The mandrel-plug 5 is now back in the original position and the control is now ready to start another cycle, as described.

25 For the backward travel of the mandrel-bar carriage 8 with the large motor 39, the latch 13 must be held in the up, or unlatched position, for the entire travel, thereby closing the contacts 112^a and 112^b of the latch limit switch 112.

30 *Manual operation*

The operator can stop, start or reverse the large motor 39 at any point in the travel of the mandrel-bar carriage 8 between the two final limit switches 110 and 108 by means of the master controller 117.

35 The operator can stop or start the small motor 26 in the forward direction at any point between the forward limit switch 110 and the point where the latch sets the latch limit switches 112 and 114 by means of the master controller 117.

40 The operator can stop, start or reverse the small motor 26 at any point beyond the point where the latch sets the latch limit switches 112 and 114 by means of the master controller 117 and the foot switch 107.

While I have shown and described one specific embodiment of my invention, it will be understood that I do not wish to be limited exactly thereto, since various modifications may be made without departing from the scope of the invention, as defined by the following claims. 5

I claim:

1. A pipe or tube mill comprising, in combination, a plurality of metal-working rolls, a mandrel-bar carriage, a mandrel-bar mounted on said mandrel-bar carriage, a mandrel carried by said mandrel-bar, means for withdrawing said mandrel-bar carriage with respect to said metal-working rolls to thereby remove said mandrel-bar and said mandrel from a rolled pipe or tube, 15 said last-named means including a heavy-duty prime mover operable to return the mandrel to a position adjacent but spaced from its fixed working position between said metal-working rolls, and a slower prime mover connected to and driving through said first-named prime mover for moving said mandrel from said spaced position into said fixed working position at a decreased rate of speed, and means for braking the drive of said prime movers. 25

2. A pipe or tube mill comprising, in combination, a plurality of metal-working rolls, a mandrel-bar carriage, a mandrel-bar mounted on said mandrel-bar carriage, a mandrel carried by said mandrel-bar, means for withdrawing said mandrel-bar carriage with respect to said metal-working rolls to thereby remove said mandrel-bar and said mandrel from a rolled pipe or tube, said last-named means including a heavy-duty prime mover operable to return the mandrel to a position adjacent but spaced from its fixed working position between said metal-working rolls, and a slower prime mover connected to and driving through said first-named prime mover for moving said mandrel from said spaced position into said fixed working position at a decreased rate of speed, means for disconnecting said prime movers, 35 and means for braking the drive of said prime movers. 40

LOUIS W. LONG.
